COMPOTE OR THE LIKE

Walter I. Bieger, Minneapolis, Minn., assignor to Arthur Salm Inc., Chicago, Ill., a corporation of Illinois

Filed Jan. 8, 1965, Ser. No. 83,367

Term of patent 14 years

(Cl. D44—15)

FIG. 1 is a perspective view of a compote incorporating my design;

FIG. 2 is an elevational view of the compote of FIG. 1; FIG. 3 is a top plan view of the compote of FIG. 1; and

FIG. 4 is a sectional elevational view of the compote of FIG. 1 taken on the line 4—4 of FIG. 3.

I claim:

The ornamental design for a compote or the like, substantially as shown.
